UNITED STATES PATENT OFFICE.

JOHN MURPHY, SR., OF PASSAIC, NEW JERSEY, ASSIGNOR OF ONE-HALF TO ROBERT MURPHY, OF PASSAIC, NEW JERSEY.

DELIVERY-FEED MECHANISM FOR MANGLES.

Application filed July 3, 1924. Serial No. 723,999.

To all whom it may concern:

Be it known that I, JOHN MURPHY, Sr., a citizen of the United States, residing at Passaic, in the county of Passaic and State 5 of New Jersey, have invented certain new and useful Improvements in Delivery-Feed Mechanism for Mangles, of which the following is a specification.

In the case of mangles or ironing machines of the type shown in the Thompson and Murphy Patent No. 863,671 the machines have to be served by two attendants, one at one side to deliver to the machine the handkerchiefs or other articles to be 10 ironed and the other at the other side to remove the ironed articles. The principal object of this invention is to provide means to be used in connection with a machine of this type whereby only one attendant will 15 be required, said means delivering the ironed articles within the convenient reach of the attendant who supplies them to the machine for the ironing thereof.

In the drawings,

25 Fig. 1 is a side elevation showing a mangle with the aforesaid means operatively associated therewith;

Fig. 2 is a rear elevation of said means;

Fig. 3 shows the ironing roll and a rotary 30 brush and a portion of the main set of endless belts in side elevation;

Fig. 4 is a fragmentary front elevation of said brush;

Fig. 5 shows in side elevation the inclined 35 plate over which the articles slide and the grooved roller around which the belts extend; and

Fig. 6 is a rear elevation of what is shown in Fig. 5.

40 The mangle or ironing machine may be the same as in the said Thompson and Murphy patent, including a frame α , the ironing roll b fixed on the shaft c journaled in said frame, the shaft d in boxes e vertically 45 adjustable in the frame, the curved smoothing plate f pivoted on the shaft d and coactive with the roll to iron the handkerchiefs, the means g for varying the pressure of the plate on said roll, the roll h pivotally 50 connected with shaft d by the links i and coactive with roll b to insure evenness of the articles preliminary to the ironing which is effected by the coaction of roll b and the smoothing plate, and the platform or shelf j 55 on which the handkerchiefs to be ironed

are placed. It is not material, however, what ironing machine or mangle is employed.

I provide a frame consisting of suitably braced side-frames k which in the present 60 case are here shown attached to the back and top of the frame α .

In this frame may be suitably supported, as at l and m , a guiding plate n which is arranged at the back of the mangle in an 65 upright position but pitched forward at an incline so that its upper end, which is preferably bent downward at an incline, as at n' , is over the mangle. This plate has projections n^2 arranged along its lower edge, as 70 shown in Fig. 6, for a purpose to be explained.

A set of parallel endless belts o coacts with the plate n to conduct the articles upwardly after said system receives the articles. Each belt in the set extends around the cylindrical body of a rotary brush p arranged near the ironing roll and also around an elongated pulley r arranged above the plate n ; the two stretches of each 80 belt also extend around other pulleys s s' arranged one relatively inward of and the other below said plate, so that the lower portion of each belt extends substantially 85 horizontally and the remaining portion upwardly and forwardly at an incline, such portion of the relatively inner stretch of the belt lying close to the plate and parallel therewith. An adjustable belt-tightening pulley is provided at t . All the pulleys are 90 preferably grooved. The brush p has its bristles p' arranged in annular groups, spaced to receive the belts between them so that it also forms a pulley. The pulleys p , s' and r receive the belts o in their grooves, 95 but the belts ride on the rises of the pulley s , as shown in Fig. 6. The projections n^2 of the plate n extend into the grooves of the pulley s , as shown in Fig. 6. The bristles of brush p wipe against the ironing roll. 100

There is another belt u . This extends around the pulley r and also around the grooved pulley v which is arranged suitably forward of the set of belts o .

On a shaft w near the upper end of the 105 plate is fulcrumed a set of deflectors x , each preferably individually movable on the shaft. Each deflector has a thin blade x' which normally rests against the inclined downwardly bent end n' of the plate n ; it 110

also has a counter-balance arm x^2 and has a nut y screwed thereon so as to form an adjusting weight.

The whole system of belts and pulleys is driven from the shaft of the ironing roll by a chain and sprocket connection z so that the direction of advance of the belts is according to the arrow in Fig. 1.

Projecting from the plate toward the front of the ironing machine and above the latter is a shelf or platform 2 to receive the articles. This is in convenient reach of the attendant serving the ironing machine from the shelf or platform j on which the articles are initially placed.

The ironing machine being in operation, the attendant removes the handkerchiefs A one by one from the shelf j and feeds them to the machine. The system of belts and pulleys being driven from the ironing roll b , as each handkerchief, clinging to the fabric surface of said roll, approaches the brush it is wiped from the surface of the roll and fed edgewise onto the horizontal portion of the inner stretch of the set of belts o and is then carried by said inner stretch of the belt set around the pulley s in contact with its high portions or rises. By the projecting portions n^2 of the plate n it is then switched away from the pulley s and made to pass upwardly between said plate and the inclined portion of said inner stretch of the set of belts. Having traversed the plate its upper edge encounters the deflectors x , which by their depending portions x' direct it downwardly so that it is delivered onto the shelf 2 in convenient reach of the attendant at the front of the machine. The pulley v prevents any possibility of the handkerchief being deflected by pressure of the air so as in falling to miss the shelf and fail to lodge thereon. The deflectors x being freely movable on their fulcrum w cause the change in travel of the handkerchiefs from the upward to the downward direction without puckering: with rigid deflectors I find that handkerchiefs or other similar thin articles frequently pucker between the deflectors and cause a jam. The mechanism necessary to convey the handkerchiefs upwardly and generally back to the front of the machine is greatly simplified by the use of the upwardly and forwardly inclined plate n .

Having thus fully described my invention, what I claim as new and desire to secure by Letters Patent is:

1. An attachment for a machine for operating on articles of sheet material having means to receive the articles at one side and deliver them at the other side thereof, comprising a supporting structure, and means in said structure, including a belt-and-pulley system, for receiving the delivered articles from the first-named means and then conveying them upwardly and over said ma-

chine and thereupon delivering them thereon at the other side.

2. In a mechanism for conveying handkerchiefs and the like, the combination of a supporting structure, a plate arranged in an inclined plane, a pulley at the upper end of the plate, another pulley offset laterally from the lower end of the plate and arranged approximately vertically beneath the first pulley, belt guiding-means arranged at the lower end of the plate, and an endless belt extending around the pulleys and between the latter having bends maintained in its two stretches by said guiding-means, that stretch of the belt which adjoins the plate cooperating with the latter to hold the handkerchiefs between them, and the belt being adapted to be advanced to advance the articles with the mentioned stretch thereof moving toward the first-named or upper

3. An attachment for a machine for operating on articles of sheet material having a revolving roll to receive the articles on its periphery at one side of the machine and convey them to the other side thereof, comprising a supporting structure, and means in said structure, including a rotary member positioned to revolve against the periphery of and revolving in the same direction as said roll when the attachment is in operative position and adapted to remove the articles edgewise from the roll, for receiving the articles from the roll and conveying them over said machine and thereupon delivering them.

4. An attachment for a machine for operating on articles of sheet material having means to receive the articles at one side and deliver them at the other side thereof, comprising a supporting structure, a plate in said structure arranged at said other side of said machine and pitched upward and toward the first-named side thereof, and means to receive the articles from the machine and convey them over the same including a lower belt-guiding member close to the machine, an upper belt-guiding member adjoining the top of the plate and other belt-guiding members arranged near the lower end of the plate, and an endless belt to advance the articles upwardly along the surface of the plate remote from the machine, said belt extending around the first two guiding members and having its two stretches respectively extending around the other two guiding members.

5. In a machine of the class described, the combination of means to advance the articles one after another in a given plane, and means to bend each succeeding article around an acute angle between said plane and another plane and thereby divert such article into the latter plane including a deflector fulcrumed on an axis substantially parallel with both planes, said deflector being nor-

mally held projecting from its fulcrum in the direction of the second plane but being yieldable on its fulcrum under pressure of the article.

5 6. In a machine of the class described, the combination of means to advance a flexible sheet article in a given plane including a set of parallel spaced belts, and means to divert the article into another plane at an angle to

the first plane including deflectors fulcrumed 10 on an axis substantially parallel with both planes and projecting between the belts, each deflector being normally held projecting from its fulcrum in the direction of the second plane but being yieldable on its fulcrum 15 under pressure of the article.

In testimony whereof I affix my signature.
JOHN MURPHY, Sr.
